[57] **CLAIM**

An ornamental design for a combination food tray and trash container, as shown and described.

DESCRIPTION

FIG. 1 is a perspective view of a combination food tray and trash container showing my new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a rear elevational view thereof;

FIG. 7 is a front elevational view thereof;

FIG. 8 is a perspective view thereof, with perforations shown in their open positions for clarity of illustration; and,

FIG. 9 is a perspective view thereof; shown in an alternate position; with its flap shown in an open position for clarity of illustration.

The broken line showing of a support in FIG. 9 is for illustrative purpose only and forms no part of the claim. Other broken lines represent break lines.
